(57) **CLAIM**

The ornamental design for fleur de lis casket, as shown and described.

DESCRIPTION

FIG. 1 is a perspective view of the inventive design in use.

FIG. 2 is a perspective view thereof;

FIG. 3 is a top view thereof;

FIG. 4 is a front view thereof;

FIG. 5 is a bottom view thereof;

FIG. 6 is a back view thereof;

FIG. 7 is a left side view thereof; and,

FIG. 8 is a right side view thereof.

The broken line showing of a casket is included for the purpose of illustrating environmental structure and forms no part of the claimed design.
